UNITED STATES PATENT OFFICE.

CLARK CHASE, OF FALL RIVER, MASSACHUSETTS, ASSIGNOR TO AMERICAN CABLEWAY COMPANY, OF FALL RIVER, MASSACHUSETTS, A CORPORATION OF MASSACHUSETTS.

HOISTING-BUCKET.

No. 859,543.

Specification of Letters Patent.

Patented July 9, 1907.

Original application filed June 6, 1905, Serial No. 263,969. Divided and this application filed March 15, 1906. Renewed December 26, 1906. Serial No. 349,444.

To all whom it may concern:

Be it known that I, CLARK CHASE, a citizen of the United States, residing at Fall River, in the county of Bristol and State of Massachusetts, have invented certain new and useful Improvements in Hoisting-Buckets, of which the following is a specification.

My invention relates to hoisting buckets, and resides in mechanical means whereby the weight of a bucket or receptacle of a load-bearing member that may be fastened, unfastened and movably secured to a sustaining member, is utilized for opening and closing the bucket for the purpose of loading and unloading the contents of the bucket.

By reason of my invention the discharging of the bucket is under easy manual control of the operator, while its closing and locking are entirely automatic. The advantages resulting from my invention will be obvious, especially when the bucket is of large dimensions, and its movably secured bottom is heavy. A reference to my application for United States Letters-Patent Serial No. 263,969, filed by me June 6th, 1905, and of which this application is a division, shows how my invention may be of great utility in connection with a movable sustaining member of a loading and unloading elevated carrier. However, for the purpose of illustrating my invention in this application, the sustaining member is assumed to be stationary.

Figure 1 shows my invention closed, and supported by a hoisting and lowering rope; said invention having just become disengaged from the hook of its sustaining member; Fig. 2 shows it open and supported by a hoisting and lowering rope; Fig. 3 shows it in engagement with the hook of its supporting member, and in the act of descending, all of which causes the bottom to close, and to become locked, as shown in Fig. 1; while Figs. 4 and 5 are a side elevation and a plan, showing details of the construction.

In the drawings illustrating the principle of my invention, and the best mode now known to me of embodying that principle, A is a load-bearing member having a receptacle, bucket or tub B, while C is a supporting member. A cross-bar 37, is designed to engage a hook 121, on the supporting member C, and is mounted in guide plates 80, which assist in guiding the load-bearing member into fastening engagement with the supporting member. Mounted between these guide plates 80 and below them, is a pulley 81; extending down from the guide plates is a rod 82 which passes through two guides 83, 84, forming part of the tub, and holding the rod 82 in a plane, say perpendicular to the plane of the tub. Pivoted to the lower sides of the tub, and forming its bottom, are two doors 85 opening downward, and pivotally connected to the free end portion of rod 82 by links 86. Mounted on the guide member 83 are two pulleys 87, one on each side of the rod; and in engagement with the side and top portion of the guide member 83, are two spring members 88, fixed to the guide plates 80, and having shoulders 89 catching and engaging said top and side portions of the guide member 83, as clearly appears from Figs. 4 and 5.

Pivoted upon the rod 82, and confined within two slotted retaining members 93 fixed to the guide member 83, is a dumping lever 90, designed to be operated by hand or by a lanyard, and having cam surfaces 91 to engage the adjacent shoulders 89 of the spring members 88. The rope 2 passes from the pulley 210 on the supporting member C, down through a guide 92, guide plate 83, round the pulley 87, up over the pulley 81, down under the second pulley 87, up through the guide plate 83, guide 92, and is made fast to, say a hook 122 upon the supporting member C.

When the cross arm 37, Fig. 1, has become detached from the hook 121, the weight of the load bearing member and the tub is sustained by the rope 2 which is engaging the pulleys 87, 81, 87; the strands of the rope 2 tending to draw the pulley 81 downward toward the pulleys 87, 87; but this tendency is counteracted by the shoulder 89, Fig. 4, of the stiff, spring members 88, engaging the edge and top portion of the guide member 83; the bottom of the tub, therefore, remains closed. The tub being detached from the supporting member, that is, movably secured to the supporting member, and ready for dumping, see Fig. 1, the dumping lever 90 is moved, as in the direction indicated by the arrow in Fig. 5, the shoulders 89 are moved out of engagement with the guide member 83, and the weight of the tub, acting on the rope 2 and its pulleys 87, 81, 87, causes the pulley 81 and the rod 82 to move downward relatively to the doors of the bottom 85, and they are forced open; all the parts appearing in the positions shown in Fig. 2. The tub, by this operation, having been dumped, it is returned to the supporting member by hauling on the rope 2; the parts of the tub remaining in the same position shown in Fig. 2, until the cross-bar 37 engages, and becomes detachably fastened to, the hook 121 of the supporting member, at which moment, the rope 2 being slackened, the weight of the tub causes the tub to descend, the guide members 83 to move down the bar 82, and the doors 85 of the bottom to begin to close, all of which is apparent in Fig. 3. The shoulders 89 of the spring members 88 slide along the edges of the guide member 83, and when they pass they snap into engagement with the guide member 83, force the cam lever 90 back into position for the next dumping of the tub, and securely close the bottom of the tub.

In fine, after the tub is unfastened from its sustaining member, in any well known way, it may be dumped at the time desired, by moving the dumping lever; and, if, after the tub is dumped, the cross-bar is lifted 5 in position above the hook, to be fastened thereto, and haul line 2 is released, the tub will become automatically closed by the action of its own weight.

As is stated above, my new receptacle, tub, or bucket, may be used with other forms of supporting members, 10 either stationary or movable, as a carriage, and, desiring to claim my invention in the broadest manner legally possible, it being understood that the salient feature of my invention may be embodied in many different forms without departing from the principle 15 thereof.

What I claim is:

1. In a load-bearing member, a receptacle adapted to be opened and closed; a member movably mounted in said receptacle; one end portion of said member being designed 20 to be detachably fastened to a support; and the other end portion of said member being operatively connected to said receptacle, to cause said receptacle to close and be held closed while the weight of the receptacle is borne by said member.
2. In a load-bearing member, a receptacle having an outlet opening therein; a device to close the outlet; a rod movably mounted in said receptacle; the adjacent end portion of said rod being operatively connected with the outlet closing device; and means whereby the rod may be detachably fastened to a support; all designed so that while 25 the receptacle is sustained from the support, the weight of the receptacle causes the outlet closing device to close the receptacle and hold it closed.
3. A load-bearing member consisting of a receptacle hav-

ing an outlet opening therein; a device to close the outlet; a rod movably mounted in said receptacle, and whose adjacent end portion is operatively connected with the closing device of the outlet; a rope, to raise and lower the receptacle, in moving engagement with the opposite end portion of the rod, and with the receptacle; means whereby the rod may be detachably fastened to a supporting member; means whereby the rod, when the outlet is closed, may be automatically locked to the receptacle, and have no movement relatively thereto; and means whereby the rod may be unlocked from the receptacle whose weight, 40 acting on the rope, causes the rod to approach the receptacle, and force open the closing device of the receptacle. 45

4. A load-bearing member consisting of a receptacle having an outlet in its bottom; a door pivoted to close said outlet; a rod movably mounted in said receptacle; a link pivots connecting the door and the adjacent end portion of the rod; a pulley mounted on the opposite end portion of the rod; two pulleys mounted on the receptacle; a rope passing over one pulley on the receptacle, the pulley on the rod, and the other pulley on the receptacle; the 50 rope being used to raise and lower the load-bearing member; a spring plate, and means to secure the same to the rod, whereby, when the outlet is closed, a shoulder on said plate automatically engages the receptacle and locks the closed door to the receptacle; a cam-lever to disengage the 55 spring plate and the receptacle, and permit the weight of the latter, acting through the rope, to force the rod downward and open the door; a cross-bar, and means to secure the same to the rod, whereby the rod may be detachably fastened to a supporting member. 60

In testimony whereof I affix my signature in presence of two witnesses.

CLARK CHASE.
